Inventor:

J. J. Chittenden

United States Patent Office.

D. D. CHITTENDEN, OF BALDWINSVILLE, NEW YORK.

Letters Patent No. 92,165, dated July 6, 1869.

MILKING-STOOL.

The Schedule referred to in these Letters Patent and making part of the same.

To all whom it may concern :

Be it known that I, D. D. CHITTENDEN, of Baldwinsville, in the county of Onondaga, and State of New York, have invented a new and useful Improvement in Milking-Stools; and I do hereby declare that the following is a full, clear, and exact description thereof, which will enable those skilled in the art to make and use the same, reference being had to the accompanying drawings, forming part of this specification, in which—

Figure 1 is a side view, with the pail-rest or platform let down in position for use, and

Figure 2 is a plan view, with the pail-rest in a folded position.

Similar letters of reference indicate like parts.

This invention relates to an improved rest or attachment for milking-stools, whereby the milk-pail is held from contact with the ground, and to an improved attachment for securing the switch or tail of the cow, so that the milkman shall not be annoyed thereby.

In the accompanying drawings—

A is the seat or milking-stool;

B is the pail-rest or platform; and

C is the switch-holder.

The rest B is hinged to a slotted standard, E, by hinge, e; and said standard E is secured to the side of the stool A by a bolt or pin, f, which passes through the slot of the standard.

To unfold the pail-rest, the standard E, fig. 2, is turned in a vertical position, and depressed on the bolt f, and the rest B is then thrown out or turned down into position, as shown by fig. 1.

The red line B, in fig. 2, also indicates the position of the rest B, when thrown out for use.

When the stool is not in use, the rest B is folded up, so that the stool is in snug form, as seen in fig. 1.

The switch-holder consists in a standard, C, which is provided with a short clamping-lever, D, having a curved portion, d, for a handle.

This lever is pivoted in a slot, c, fig. 2, in the standard, and the slot is extended downward, so that the whole of the lever D, to its handle, enters the slot, when downward pressure is applied to said handle.

To secure the tail or switch, the hairs at its end, or a few of them, are carried under the lever D, and the lever being pressed down, said hairs are pressed into the slot c, with the lever, and in this manner are held with a sufficient grasp to prevent the annoyance to the milkman of being switched thereby in the efforts of the cow to keep off flies.

By this means, the pail is kept from contact with barn-yard dirt, and the stool is in snug form only when in use, and the switch-holder is constructed in the most simple manner.

Having thus described my invention,

What I claim as new, and desire to secure by Letters Patent, is—

1. In combination with the stool A, the pail-rest B b, hinged to the slotted standard E, in such manner as to be adjustable and capable of folding up, when said parts are constructed and arranged substantially as herein shown and described.

2. The clamping-lever D d, in connection with the standard C and milking-stool A, all constructed and operated as and for the purpose herein set forth.

The above specification of my invention signed by me, this 13th day of May, 1869.

D. D. CHITTENDEN.
